CLAIM

The ornamental design for a shopping cart-ring shaped paper holder, as shown and described.

DESCRIPTION

FIG. 1 is a rear perspective view of a shopping cart ring-shaped paper holder;

FIG. 2 is a front perspective view thereof;

FIG. 3 is a front view thereof;

FIG. 4 is a right side view thereof, the left side view being a mirror image of the right side view;

FIG. 5 is a rear view thereof; and,

FIG. 6 is a bottom view thereof.
